SCREEN BAR FOR CRUSHING MACHINERY

Filed June 29, 1928

INVENTOR:
James E. Stine,

Murray B. Boyer
Atty

UNITED STATES PATENT OFFICE

JAMES E. STINE, OF ALDAN, PENNSYLVANIA, ASSIGNEE TO PENNSYLVANIA CRUSHER COMPANY, OF NEW YORK, N. Y., A CORPORATION OF NEW YORK

SCREEN BAR FOR CRUSHING MACHINERY

Application filed June 29, 1928. Serial No. 289,251.

My invention relates to crushing machinery, more particularly hammer crushers, employed in the reduction of coal, ore, stone, and the like, and one object of my invention 5 is to provide an improved form of screen bar employed in making up the discharge grid or screen of structures of this type; such grid or screen being disposed substantially concentric with respect to the path of the 10 hammers which effect the breaking and/or crushing of material operated upon by beating such material against the edges of the bars making up such grid or screen.

A further object of my invention is to 15 provide a self-spacing bar; such bar having lateral projections disposed at intervals, which projections may be disposed upon opposite faces of the bar and integral therewith or not, as the case may be.

20 And a still further object of my invention is to provide a bar having interlocking means whereby it may be held against radial movement; such interlocking means being associated with the spacing lugs or projections.

25 My improved grid or screen bar, having a substantially rectangular contour, is of the reversible type so that when one active edge is worn, it may be reversed by turning the same upside down or end for end, as the case may be, in order that all four active edges 30 of the bar may be brought into cooperative relation with the grid or screen.

These and other features of my invention 35 are more fully described hereinafter; reference being had to the accompanying drawings, in which:

40 Figure 1 is a cross sectional elevation, more or less diagrammatic in character, of one form of crushing machinery in which my improved screen bar may be employed.

Fig. 2 is a perspective view of one of the bars shown in Fig. 1.

Fig. 3 is an end elevation of a pair of the bars shown in Figs. 1 and 2.

45 Fig. 4 is a perspective view of modified form of interlocking bar within the scope of my invention, and

Fig. 5 is an end elevation of a pair of bars 50 of the type shown in Fig. 4.

My improved screen bar is available for

use with many forms of crushing machinery, more particularly those of the hammer type, and Fig. 1 illustrates more or less diagrammatically a hammer crusher having the usual cage or frame 1, pivotally mounted at 2, and 55 having semi-circular grooves 3 at the sides, providing seats for the reception of the ends of bars 4, which make up the grid or screen constituting the cage and against which the crushing or breaking action takes place under the action of hammers such as indicated 60 at 5. These hammers may be pivotally mounted on rods 6, carried by disks 7, supported by a shaft 8; such parts constituting the rotor element of the crushing machine. 65 The frame or cage 1, carrying the bars 4, is pivotally mounted in the usual manner, so as to permit adjustment of the grid or screen formed by said bars 4 with respect to the 70 path of the hammers.

A bar of one construction or arrangement within the scope of my invention is clearly shown in the perspective view, Fig. 2, and may comprise a section of steel or other suitable metal, of material length, having a rectangular or substantially rectangular cross sectional contour, with projections 10 disposed at intervals throughout its length. These projections may be integral with the body of the bar, and they are disposed inwardly a slight distance with respect to the active edges of the bar. The projections 15 are preferably beveled in two directions with respect to the side faces of the bar, so that when disposed in the crusher structure to 20 form the grid or screen of the crushing structure in proper relative position with respect to the rotor element one of the beveled faces of each of such projections will be in contact substantially throughout its entire area with 25 a similar beveled face of the projection of an adjacent bar, and such contacting surfaces will lie in radial planes or in planes substantially parallel to radial planes passing 30 throughout adjacent bars. In the form of 35 bars illustrated herein, each face of the same is provided with spacing projections and the extent of their lateral projection with respect to said bars determines the distance 40 between the several bars in the formation of 45

50 55 60 65 70 75 80 85 90 95 100

My improved screen bar is available for

the grid or screen, which distance may differ for different types of material undergoing crushing action.

In addition to the arrangement providing for contact of the beveled faces of the projections of the several bars, these projections are arranged for interlocking engagement with each other. For this purpose I provide each projection 10 with complementary 10 engaging means in the form of recesses and lugs. In the type of bar illustrated in Figs. 1, 2 and 3, each projection 10 is provided with a recess 11 and a lug 12; such recesses and lugs having the same contour so that 15 the lug of one projection may fit the recess formed in the projection of an adjacent bar, and vice versa. By the use of such interlocking means the bars are held against radial movement, and chattering of the bars when 20 the machine is in action is prevented. As the bars are maintained in position with respect to each other and to the path of the hammers, any tendency of the bars to jump out of position and occasion additional wear both 25 in their seats and on the active edges of the same is avoided.

In the form of bar illustrated in Figs. 4 and 5, the several projections 10 are provided with single lugs 12^a or recesses 11^a, and in 30 order that single bars of such arrangement may have their position altered with respect to the adjacent bars without dismantling the entire set, the projections at one end and one side of the bar may have recesses and 35 those on the same side and at the opposite end of the bar may have lugs; the oppositely disposed projections being provided with complementary lugs and recesses in reverse arrangement, as clearly indicated in Figs. 4 and 5. When such form of bar is reversed to change the active cutting edge from *a* to *b*, for instance, it will be simply turned from 40 end to end without changing its radial position. The form of bar shown in Figs. 1, 2 and 3, however, will be reversed in a radial 45 direction if a single bar is replaced. In both instances the replacement or reversal of a complete set of bars may be in either direction, as may be desired.

50 It will be understood that I may provide a bar of the type illustrated in Figs. 4 and 5, in which all of the projections on one side of the bar have lugs and those on the other side have complementary recesses, without de- 55 parting from my invention.

By preference, the projections are integral with the bars although it will be understood that such projections may be secured to the bars by riveting or in any other suitable 60 manner, as in the form of bar illustrated in the patent of George W. Borton, No. 1,624,886, dated April 12, 1927, and in some instances such projections may be welded to the bars. By preference, each bar is provided 65 with a plurality of these projections, al-

though it will be understood that a single set of projections, adjacent each end of the bars may be sufficient under some conditions and with some types of crushing machinery.

As in the bar forming the subject of the 70 Borton patent referred to, my improved bars are reversible and replaceable so as to take advantage of all four of the working edges which may be successively brought into proper position relatively to the direction of 75 movement of the hammers.

80 Preferably, the several projections will be beveled in the same manner indicated; the recesses and lugs of such projections being struck from axes coinciding with the planes of the beveled portions of each projection and the faces of such beveled portions being tangent to the plane of the side walls of the bars with the contacting portions of such beveled planes lying in radial planes or in planes 85 substantially parallel with radial lines passing through adjacent bars. Such arrangement is not essential, however, and in some instances the beveling of the meeting faces of the projections may be greater, or omitted 90 entirely, so long as proper cooperation of the interlocking elements is effected.

95 While I have shown interlocking projections which are curved and substantially semi-circular in contour it will be understood that such projections may be of any shape or contour capable of interlocking engagement, without departing from my invention.

I claim:

100 1. A screen bar for crushing machinery having a plurality of spacing lugs projecting from a face of said bar at right angles with respect to the longitudinal axis thereof; each lug being provided with cooperative interlocking means for complementary engagement with the lugs of an adjacent bar.

105 2. A screen bar for crushing machinery having a plurality of spacing lugs disposed inwardly with respect to the edges of the bar and projecting from a side thereof at right angles with respect to the longitudinal axis of the bar; each lug being provided with cooperative interlocking means for complementary engagement with the lugs of an adjacent bar.

110 115 3. A screen bar for crushing machinery having a plurality of spacing lugs disposed inwardly with respect to the several edges of the bar on both sides of the same and projecting at right angles with respect to the longitudinal axis of the bar; each lug being provided with cooperative interlocking means for complementary engagement with the lugs of an adjacent bar.

120 125 4. A screen bar for crushing machinery having side projections extending laterally for contact with similar projections of an adjacent bar; certain of said projections having lugs and others being recessed for inter-

locking engagement with similar projections of an adjacent bar.

5. A screen bar for crushing machines of the hammer mill type comprising rectangular members whose ends are arranged to seat in semi-circular channels and having spacing projections on opposite sides of the same; each of said spacing projections having a lug and recess for complemental engagement 10 with recesses and lugs of a similar spacing projection of an adjacent bar.

6. A screen bar for crushing machines of the hammer mill type comprising rectangular members whose ends are arranged to seat 15 in semi-circular channels of the crushing machine and having spacing projections arranged in oppositely disposed pairs on the respective sides of the same; each of said spacing projections having inwardly beveled 20 faces provided with a lug and recess for complemental engagement with recesses and lugs of a similar spaced projection of an adjacent bar.

In witness whereof I have signed this specification.

JAMES E. STINE.
